UNITED STATES PATENT OFFICE.

THOMAS SIMMONS HOMANS, OF BROOKLYN, NEW YORK, ASSIGNOR TO MERGENTHALER LINOTYPE COMPANY, A CORPORATION OF NEW YORK.

LINOTYPE-MACHINE.

No. 851,238.

Specification of Letters Patent.

Patented April 23, 1907.

Application filed November 6, 1903. Serial No. 342,248.

To all whom it may concern:

Be it known that I, THOMAS SIMMONS HOMANS, of the borough of Brooklyn, county of Kings, and State of New York, have invented a new and useful Improvement in Linotype-Machines, of which the following is a specification.

This invention has reference to machines such as represented in Letters Patent of the United States No. 436,532, and kindred machines commonly known and sold under the trade mark "Linotype," wherein type metal printing bars or slugs are cast in a slotted mold against a composed line of matrices presented momentarily to the face of the mold, the molten metal being delivered into the mold from the mouth of a melting pot which is, for the time being, seated against the back of the mold to close the same. These molds are made in a manner well understood in the art, with removable or adjustable liners for changing the length and width of the slot, in order that slugs of different length and thickness may be produced as demanded. Repeated heating and cooling of these molds, which are made of hardened steel, the irregularity of the heating due to adjustment in the dimensions of the slot, the fact that the hot mouth of the pot is seated against the rear side only, and other conditions which occur in practice, cause the frequent warping or twisting of the molds. It is important that they shall be absolutely straight and true.

The object of my invention is to prevent the mold from acquiring excessive temperatures and to neutralize the heating influences to which they are subjected, and to this end it consists in combining with the mold a cooling plate or surface arranged to contact with the mold, preferably a plate having its temperature reduced by means of water, or other cooling medium delivered therethrough.

I am aware that the molds of type-casting machines have been constructed with internal chambers or passages through which water was circulated for the purpose of directly cooling the mold. In a linotype machine, in which the slugs produced represent a very large amount of molten metal compared with that in type bodies, and in which the size of the mold cavity is frequently and widely changed and the mold required to travel

bodily from one position to another, it is impossible to form the mold with water-receiving cavities, because the necessary employment of joints in the water connections would inevitably lead to the occasion of leakage of water into the metal-receiving cavities, and to consequent explosions, which would endanger both the machine and the attendant. For this reason, I employ a solid mold,—a mold without water chambers—and a wholly distinct or independent cooling chamber to which the mold is repeatedly presented.

In the drawings I have shown my improvement in its preferred form applied to a Mergenthaler linotype machine.

Figure 1 is a front elevation of the mold and its supporting disc with my improvement in operative relation thereto, the cooling devices being shown in dotted lines. Fig. 2 is a cross-section on the line 2—2 of Fig. 1. Fig. 3 is a face view of the cooling chamber on an enlarged scale. Fig. 4 is a top plan view of the same.

Referring to the drawings, A represents the mold having therethrough from front to rear the slot or mold cell a in which the slug or linotype is cast. In the form shown, the mold consists, as usual, of cap and body portions separated at the ends by intervening liners which are removable at will for the purpose of changing the size of the mold-slot in the manner commonly practiced in the art. The mold is firmly secured in a vertical intermittently rotated disc B, mounted on a central stud or journal C, carried by an arm 90 projecting laterally from the horizontal slide D, this arrangement permitting the disc to be freely rotated and also allowing it to be moved bodily forward and backward in order to carry the mold toward and from the matrix line.

E represents a horizontal ejector blade mounted in one side of the slide D in such manner that when the mold containing the slug is brought opposite the ejector, the latter may be advanced through the mold in order to deliver the slug therefrom between the usual trimming devices into the receiving galley.

F is a yielding guide in a support G secured to the slide D, as usual, and bearing against one side of the ejector blade to hold it in proper position.

So far as described, the parts are of ordinary construction and operate in the ordinary manner familiar to all persons skilled in the art, the disc B presenting the mold in a horizontal position, as shown by dotted lines in Fig. 1, during the casting operation, and thereafter turning it to a vertical position and in contact with the cooling body, as shown in full lines.

Passing now to my improvement, H represents a plate of copper or similar material, secured to the support G, or the guide D, or both, its front face being flattened and adapted to form an intimate contact with the rear face of the mold when the latter is in the ejecting position. This cooling plate is slotted for the passage of the ejector therethrough, and is provided with a passage h extending around the slot and connected at the end with a water supply pipe h', and a drainage pipe h'', by means of which water or other cooling fluid may be flowed continuously through the plate in order to keep the same at a low temperature.

Under ordinary circumstances, it will be sufficient to make the plate of a size substantially corresponding to that of the mold, but it may be enlarged or extended in the path of the mold to any desired extent in order to prolong the period of contact.

The plate, if properly cooled, will rapidly absorb heat from the mold and exert a marked influence, preventing the over-heating or the irregular heating of the mold. In other words, it will tend to keep the temperature of the mold within such limits as to prevent excessive or irregular expansion.

The essence of the invention lies in combining with the mold, whatever its form, and without regard to the manner in which it is supported or carried, an external cooling body of any suitable form adapted to contact with the mold.

It is to be observed that the fluid passages shown herein are closed, or in other words, are without joints or openings of any kind adjacent to the mold. This permits of the use of water or other cooling liquid as a cooling medium without danger of leakage into the mold, where its presence would be attended with disastrous results on the admission of the molten metal.

When air or other gaseous medium is em-

ployed for cooling purposes, small openings may be made in the plate G to permit the air to escape and contact with the mold, but under ordinary conditions this is not recommended.

It is to be observed that the cooling means which I have provided form no part of the mold, but are distinct and independent therefrom.

The cooling medium does not enter the mold, and there are no movable joints or openings through which the water can, by any possibility, reach the surfaces with which the molten metal contacts.

Having described my invention, what I claim is:—

1. In a linotype machine, a mold in combination with an independent cooling body arranged to contact therewith.

2. In a linotype machine, a slotted mold, an independent cooling body, and means for carrying the mold into and out of contact with said body.

3. In a linotype machine, a slotted mold in combination with an independent cooling body arranged to contact therewith, and means for artificially cooling said body.

4. In a linotype machine, the combination of a slotted mold, its revoluble supporting disc, and a fixed cooling plate or body H independent of the mold proper and arranged to contact with the rear face of the mold.

5. In a linotype machine, a slotted mold, its rotary supporting disc, a slide supporting the disc, and a mold-cooling body distinct from the mold carried with said slide.

6. In a linotype machine, the combination of a slotted mold and an independent external cooling body arranged to contact with the rear face of the mold, said body being slotted for the passage of the ejector therethrough.

7. The combination of the mold A, the rotary disc B supporting the same, and the non-rotating cooling body H distinct from the mold arranged to contact with the rear face of the disc.

In testimony whereof I hereunto set my hand this thirty first day of October, 1906, in the presence of two attesting witnesses,

THOMAS SIMMONS HOMANS.
